[57] ABSTRACT

A fixture for mounting to a vehicle. A loop of a lead is pushed through an access opening, past a connector which has a flexible leg and a cutting edge at the end of the leg. When the lead loop is pulled back, the cutting edge pierces the lead insulation and makes electrical contact with the wire within the lead. The fixture may be surface mounted to an external vehicle surface and may mount a light bulb.

6 Claims, 8 Drawing Figures

LIGHT FIXTURE FOR VEHICLES

BACKGROUND

Many vehicles such as, for example, trailers, mobile homes, and other vehicles utilize light fixtures which are installed on the external surface thereof. Any way of cutting the assembly costs and time, while concurrently maintaining or improving the functional aspects of the fixture would of course be highly desirable.

In typical existing fixtures, the wire leads are stripped, inserted through the unit and thereafter appropriately connected to contacts, either by soldering or other well known expedients, e.g., winding around screws.

Any one who has done wiring can appreciate the difficulty of such assembly steps on a production basis both in terms of production efficiency and reliable satisfactory electrical connections.

SUMMARY OF THE INVENTION

In accordance with the present invention, there is provided a relatively simple light fixture easily affixed to a vehicle and which can be wired safely, rapidly and reliably on a production basis.

The fixture in accordance with the present invention may be a reflector base member and may include a housing or base plate adapted to be attached to a vehicle such as to the external surfaces of trailers or recreational vehicles and which incorporates an integrally formed bushing or grommet extending through the surface or skin of the vehicle to define a lead access opening adapted to have passed therethrough the electrical wiring to be connected to the fixture.

The fixture of the present invention is adapted to accommodate both the ground and hot leads, can accommodate wiring of varying sizes and yet efficiently and simply permits the desired electrical connection to be effected.

In accordance with one aspect of the present invention, electrical connection is provided by a spring-like or resilient connector which intersects or at least partially overlies the lead access opening in the fixture housing through which the wires or leads pass, there being a connector for each wire. The edge of each connector, overlying the access opening, defines means to sever the insulation of a lead passed therethrough and to make contact with the electrically conductive wire contained within the insulating sheet.

Each connector is affixed to the housing and has a portion remote from its wire connecting end adapted to make contact with a light bulb, one connector maintaining contact with and retaining the ground side of the bulb and the other connector making contact with the hot side or center contact of the bulb.

More specifically, the fixture of the present invention incorporates insulative housing or base plate which in a typical embodiment is generally circular in plan view having at least one major access opening defined by an integrally formed bushing or grommet extending rearwardly therefrom. The bushing extends out the back of the base plate and is adapted to pass through a hole cut in the surface to which the base plate is to be mounted. The base plate incorporates suitable means to allow attachment thereof to the surface.

At the internal reaches of the access opening, the base plate incorporates an insulating partition which

5 may be formed integrally therewith to divide the access opening into two halves or sections each of which is adapted to receive one of the electrical leads. The partition in conjunction with the bushing defines an access opening for each lead of varying area to allow for insertion therein of different size electrical leads.

10 Overlying a portion of each of the lead apertures is a serrated or toothed end of a resilient electrical connector which is affixed to the base plate of the fixture at a point spaced from the serrated end thereof. The base plate may have other suitable positioning members to facilitate their attachment and assembly to the base plate.

15 One connector incorporates a suitable bulb clip or socket adapted to receive and retain a light bulb therein and to make electrical contact with the grounded side thereof. The other connector is adapted to make contact with the center contact of the light bulb in order to complete the electrical circuit through the bulb.

20 In operation, each lead is electrically attached to the connector by inserting the lead through the appropriate lead access opening and pushing it past the serrated end of the resilient connector causing the end to flex in the direction of movement of the wire being inserted. The lead is then pulled back slightly causing the connector to be forced against a surface of the base plate and to cut through and pierce the insulation and to 25 make contact with the electrical wire.

25 Thus, the fixture of the present invention permits reliable, simple, rapid insertion and connection of the electrical leads thereto insuring proper electrical connections, all without utilization of screws or other attachment devices.

30 Numerous other advantages and features of the present invention will become readily apparent from the following detailed description of the invention and of one embodiment thereof, from the claims and from the 35 accompanying drawings in which each and every detail shown is fully and completely disclosed as a part of this specification, in which like numerals refer to like parts.

45 BRIEF DESCRIPTION OF THE DRAWING

FIG. 1 is a diagrammatic view of a surface to which the fixture is to be mounted showing in dotted line the general positioning of the perimeter of the base plate thereon;

50 FIG. 2 is a plan view of the front of the base plate; FIG. 3 is a plan view similar to FIG. 2 showing the resilient connectors;

FIG. 4 is a back view of the base plate of a fixture of FIG. 3;

55 FIG. 5 is a sectional view taken along the lines 5-5 of FIGS. 3 and 4;

FIG. 6 is a sectional view taken along lines 6-6 of FIG. 3 and showing in dotted line the positioning of a bulb;

60 FIG. 7 is a perspective view of one of the connectors suitable for use in the present invention; and

FIG. 8 is a perspective view of one embodiment of another of the connectors suitable for use in the present invention.

65 DESCRIPTION OF SPECIFIC EMBODIMENT

While this invention is susceptible of embodiment in

many different forms, there is shown in the drawings and will herein be described in detail one specific embodiment, with the understanding that the present disclosure is to be considered as an exemplification of the principles of the invention and is not intended to limit the invention to the embodiment illustrated.

The fixture of the present invention is adapted to be easily secured as to the exterior surface of a mobile home, trailer or other vehicle with minimal preparation of the vehicle for the fixture. As seen in FIG. 1, a surface 10 to which the fixture is to be attached is prepared simply by cutting or punching a suitable hole 12 therein through which a portion of the fixture base may be inserted. The fixture itself includes a base plate 14 which is generally circular in plan view and includes a generally planar central portion 16 and a peripheral rib 18 formed perpendicularly to the central portion 16. The peripheral rib 18 includes a rearwardly extending outwardly offset spacer 20 adapted to engage the surface 10 on which the fixture is mounted. Caulking material may desirably be positioned between the surface 10 and the back of central portion 16 to provide a water-tight seal.

The planar central portion 16 is formed with an integral bushing 22 adapted to pass through the hole 12 cut out in the mounting surface 10. The bushing 22 defines a lead receiving aperture or access opening 24. The lead access opening is divided in half by an integrally formed insulating partition which may take the form of a rib 26 as seen in the drawing. The insulating partition rib 26 is stepped at 28 or otherwise configured to vary the width of each lead access opening 24a, 24b, thereby accommodating different sizes and thicknesses of leads within single openings.

The base plate 14 includes suitable means such as a pair of holes 30, 31 for accommodating fastening means, such as screws (not shown) for attaching the fixture to the metal surface 10. Hole 31 is positioned to confront one of the connectors to ground that connector to surface 10 when screwed thereto; hole 30 is remote from the connectors, thereby to guarantee proper grounding of the fixture and to assure proper polarity. The planar central portion 16 also includes connector positioning means in the form of integrally formed posts 32, 34 and rib 36 adjacent to and along one edge of the access opening 24.

A pair of connectors 38, 40 are adapted to be positioned within the central portion 16 for making electrical connection to the leads 42, 44 inserted through the access opening 24.

The hot lead connector 38, shown in FIG. 7, includes a lead connecting leg 46 having a first aperture 48 therein adapted to fit over the positioning post 32 and a second aperture 50 adapted to receive a fastener such as a rivet or eyelet 51 for securing the connector 38 to the base plate 14. The leg 46 of the connector 38 terminates at one end in a pair of fingers 52, 54 formed by a slot 56 opening in enlargement 56A extending along the center line of the leg 46, thereby allowing each of the fingers 52, 54 to flex independently of the other to accommodate different size leads. Flexing is enhanced by V-notches 57 which cooperate to provide a hinge line thereacross. When in position, as seen in FIG. 3, the ends of the fingers 52, 54 which are formed with insulation cutting teeth or serrations 58, overlie a portion, such as about one-half of the access opening 24a to one side of the partition rib 26. The combination of

the staggered or stepped partition rib portion and the pairs of fingers enables the fixture efficiently and effectively to make contact with leads of different lead thicknesses with a single fixture.

5 The opposite end 60 of the connector 38 is formed at a 90° angle and extends up from the surface of the base plate 14 to define a contact adapted to engage the central contact 62 of a bulb 64 that is retained in position by the ground connector 40, shown in FIG. 8.

10 The ground connector 40 is a generally U-shaped member, having a lead engaging leg 66 generally similarly configured to the leg 46 of the hot lead connector 38. Thus the leg 66 of connector 40 includes an aperture 68 adapted to fit over the positioning post 34. The 15 connector leg 66 terminates in a pair of fingers 72, 74 separated by an axial slot 76 (opening in an enlargement 76A) which permits each of the fingers 72, 74 to flex independently and to receive the lead inserted into the other half 24b of the lead access opening 24. Flexing is enhanced by V-notches 77. The ends of the fingers 72, 74 are also serrated or formed with teeth 78.

20 The other leg 80 of the U-shaped connector 40 has an aperture 81 to receive a rivet or eyelet 53 for affixing it to the base plate and terminates at its free end in a bulb receiving clip 82 to receive the shank 84 of the light bulb 64 and to make electrical contact therewith, as seen in FIG. 6. When the light bulb 64 is positioned in the bulb clip 82, the center contact 62 of the bulb 64 engages the bulb contact 60 of the hot lead connector 38 to complete the electrical circuit through the bulb.

25 The leads 42, 44 are connected to each of the connectors 38, 40 simply by inserting each lead 42, 44 through the appropriate half 24a, 24b of the access opening 24 and pushing each lead 42, 44 past the respective teeth 58, 78 of the fingers 52, 54 and 72, 74. As a lead 42, 44 is pushed past the end of its connector 38, 40, one or both of the fingers flex, allowing the lead 30 to pass. When a sufficient amount of the lead has been inserted and forced past the connector, it is pulled back slightly, pulling the fingers back toward and against the surface of the central portion 16 and causing the teeth to cut through the lead insulation and to make electrical contact with the wires within the insulated lead, simultaneously pinning the lead against the partition rib 26. Rib 26 is radiused at 26A, thereby to permit the leads 42, 44 easily to be pulled back and to minimize resistance to the pulling back into electrical contact with the connector teeth. The electrical connection is thus secured and the connector is restrained from flexing into the access opening by the planar surface of the base central portion 16. Solid and secure electrical connection is thereby effected.

35 50 55 Preferably leads 42, 44 are inserted in looped form. This facilitates insertion and permits using wire runs which are continuous through two or more stations in the vehicle, saving time and labor in providing the electrical connection.

60 65 The peripheral rib 18 of the base plate 14 incorporates a bead 90 to snap mount a typical cover (not shown) which protects the interior of the fixture and permits the light, when illuminated, to be seen there-through.

A condensate escape passage 91 is provided by a narrow break in the bead 90 and by a slight relief in the main body of the rib 18 immediately below the break

in the bead. Condensate will follow the direction of arrows A as shown in FIG. 5 in escaping through passage 91.

Thus, there has been disclosed a fixture which requires minimal preparation of a surface to which it may be attached, which permits ready assembly of the fixture itself and which permits rapid, simple and reliable connection of leads to fixture connectors, thereby to complete an electrical circuit. Such fixtures are particularly useful for mounting light bulbs to external vehicle surfaces, although it will be apparent that they are adapted to other applications as well.

From the foregoing, it will be apparent that variations and modifications may be effected without departing from the true spirit and scope of the invention. It is, of course, intended to cover by the appended claims all such modifications as fall within the scope of the claims.

I claim:

1. A fixture for lights adapted to be mounted on a surface comprising an electrically insulative base member defining an access opening therethrough, a partition member dividing said access opening, said partition member being configured to vary the width of each portion of said access opening to accommodate leads of varying diameter, a pair of electrical connectors, each having a free end portion overlying a separate portion of said access opening on opposite sides of said partition member and affixed to said base member at a point spaced from said free end, said free end defining cutting means adapted to pierce the insulation of a lead pulled back in said access opening, said free ends flexing away from said base in response to the insertion of a lead through said portion of said access opening from the rear thereof and piercing the insulation of said lead in response to said lead being pulled in said portion of said access opening to make electrical contact with the wire therein.

2. A fixture as claimed in claim 1 wherein one of said connectors is generally U-shaped, said free end being formed at the end of one leg of said U-shaped connector, the other end of said U-shaped connector defining a light bulb retaining electrical contact, the other of said connectors defining contact means adapted to engage the other contact of a bulb retained by said one connector.

3. A fixture as claimed in claim 1 wherein said base member includes first and second positioning members

formed integrally therewith and engaging the connectors to define the position of said connectors affixed thereto, said first positioning members passing through each of said connectors, and said second positioning member engaging one edge of each of said connectors.

4. A fixture as claimed in claim 1 wherein said base member includes a generally annular bushing formed integrally therewith and extending rearwardly from the back thereof, said bushing defining said access opening, and wherein said partition member has a stepped configuration to define a pair of access openings on either side thereof, each of said pair of access openings having a first portion and a second portion, one of said portions being wider than the others thereby to accommodate leads of different thicknesses.

5. A fixture as claimed in claim 1 wherein one of said connectors is a generally U-shaped planar electrically conductive member having a first leg thereof terminating in a pair of independently flexible fingers, the ends of each of said fingers defining insulation cutting means overlying said access opening, and having a second leg including a bulb receiving clip adapted to retain a bulb therein in electrical contact therewith, each of said connectors defining an aperture adapted to fit over a post in said base member for properly positioning said connector and a second aperture for receiving an attachment device for affixing said connector to said base member.

6. A method for connecting an insulated electrical lead to a fixture of the type having a base member, an access opening formed in said base member, a partition member dividing said access opening into two portions, electrical connectors attached to said base member, each said connector having at least one free piercing end overlying a portion of the access opening, with said free end being capable of being flexed, including the steps of forming a loop in said lead, inserting said loop into said access opening, forcing said lead loop past said free end of one of said connectors to effect flexing thereof, pulling said lead loop back slightly to pull said flexed free end of said connector toward its original unflexed position and to force said lead loop against said partition member and thereby to cause said free end to pierce the insulation of said lead to effect electrical contact between said free end of said one connector and said lead.
